BY
Cornelia C. Billings
ATTORNEY

UNITED STATES PATENT OFFICE.

NATHAN HATCH, OF ALBANY, NEW YORK.

GARMENT.

1,303,663.

Specification of Letters Patent. Patented May 13, 1919.

Application filed November 4, 1918. Serial No. 261,136.

To all whom it may concern:

Be it known that I, NATHAN HATCH, a citizen of the United States, and a resident of Albany, county of Albany, State of New York, have invented certain new and useful Improvements in Garments; and I do declare the following to be a full, clear, and exact description of the invention, such as will enable others skilled in the art to which it appertains to make and use the same.

This invention relates to an article of wearing apparel for men, women and children and is particularly adapted for undergarments such as union suits, but is not confined thereto.

One of the objects of the invention is to construct a garment which will fit the body of the wearer perfectly and securely, and to make it very easy to put on and take off.

Another object is to construct a garment in which it is not necessary to provide an objectionable number of fastening means and objectionable lines of buttons and buttonholes or other securing means.

The garment is so constructed that it may be easily donned and as easily slipped off the body of the wearer, yet while being worn it is securely and effectually held in place upon the body due to the new and particular construction thereof at the shoulder, chest and neck portions.

Referring to the drawing:

Figure 1 is a front view of an embodiment of my invention shown in a combination garment.

Fig. 2 is another view of the front of the upper portion of a garment embodying my invention, the garment being shown with one of the chest flaps open.

Fig. 3 is a front view of the pattern blank of the upper or body portion of the garment.

Fig. 4 is a perspective view of my garment in the position the parts assume when the upper or body portion is either being donned or removed from the body of the wearer.

The garment may be made either of woven or knitted fabric, and except for the features of construction which constitute my invention it is made in the usual way, namely, the leg portions may be long or short, the arm portions long or short or they may be omitted altogether; the leg and arm ends are ribbed and finished in the usual manner, and the arm holes and border about the neck and body flaps are also finished in the usual way.

The garment may also be provided with an open and overlapping fly construction and it is provided with the usual open and overlapping substantially longitudinal opening in the seat portion thereof.

The seat portion is constructed in the usual way by means of two substantially triangular patterns or inserts which are secured to the garment and to each other, and a fastening means, as usual, may be provided therefor.

In the drawing, A represents the body portion of the garment, and B the leg portions. Extending upwardly from the points 2 and 3 on the respective sides and each at a substantial distance below the arm pits is a back flap C and two similarly shaped chest flaps D and E.

The back flap C is formed between the points 2 and 3 and 8 and 9, respectively, the line between the points 8 and 9 being curved to fit the back of the neck of the wearer and to form shoulder flaps M, N for the purpose hereinafter described.

The chest flaps D and E are formed between the points 2 and 4 and 3 and 5, and a medial line extending along the front from the point 6 to the point 7, the said point 6 being situated approximately in a horizontal line between the points 2 and 3.

An opening for the neck is formed by cutting a V-shape on the lines extending from 7 to 4 and from 7 to 5.

A single fastening means which may be a button *a* and buttonhole *b* or any other suitable means such as a string or pin, is provided at the point 7 to secure the chest flaps together at that point, and the two upper corners of the back flap forming shoulder flaps M and N are folded over the respective upper corners of the front flaps forming shoulder flaps O and P and secured together along the upper boundary of the armhole as by stitching or any other suitable means from approximately the points 10 and 11; 12 and 13.

An additional button hole *c* is placed near the button *a*, so that should the button *a* become detached an ordinary collar button 105 may be used in connection with the two buttonholes to secure the chest flaps together at that point.

As has been heretofore described in prior patents issued to me, it is preferable to turn 110 and secure the back shoulder flaps over the front shoulder flaps so that the suspenders

of the wearer will not cause a buckling of either flap, which might be the case should the front shoulder flaps be turned over the back shoulder flap.

- 5 With my improved construction when the garment is adjusted in place upon the body of the wearer, the shoulder portions fit into the natural contour of the body and the central chest flaps may then be secured together 10 at the point 7. The result is a neat fitting, and readily donned and doffed garment provided with a minimum amount of fastening means, thus affording a great saving to the manufacturer and ultimately to the individual user of the garment.

From the above description and with special reference to the illustration in Fig. 4, it will be appreciated that the construction 20 of my improved garment is such that when the chest flaps are unfastened, the wearer is enabled to provide a maximum opening in the top of the garment by means of which it may be readily slipped over the body and adjusted to the shoulders in donning the 25 same, and on the other hand it may be readily dislodged from the shoulders and slipped off the body of the wearer.

Having now described my invention what 30 I claim as new and desire to secure by Letters Patent is:

1. In a garment, a trunk portion, a single back flap and a pair of chest flaps comprising the chest covering, each of the said three flaps extending upwardly from the 35 trunk portion, the upper corners of each flap forming four shoulder portions, the two shoulder portions of the back flap each extending respectively over the single shoul-

der portions of each of the two chest flaps, the shoulder portions of the back flap being secured respectively to the shoulder portions of each of the chest flaps at their respective outer edges.

2. In a garment, a trunk portion, a single back flap and a pair of chest flaps comprising the chest covering, each of the said three flaps extending upwardly from the trunk portion, the upper corners of each flap forming four shoulder portions, the two shoulder portions of the back flap each extending respectively over the single shoulder portions of each of the two chest flaps, the shoulder portions of the back flap being secured respectively to the shoulder portions of each of the chest flaps at their outer edges, and means for removably securing a pair of flaps comprising the chest covering one to the other at a medial point.

3. In a garment, a trunk portion, a single back flap substantially rectangular in shape, the upper corners thereof forming shoulder portions, a pair of similarly shaped substantially triangular chest flaps, the upper corner of each forming a shoulder flap, the said shoulder flaps on each side being secured together at their outer edges, and means for removably securing the chest flaps together at a medial point, the pair of chest flaps meeting each other below the securing means on a substantial vertical line.

In witness whereof I have hereunto set my hand at the city of Albany, county of Albany and State of New York, this 23 day of October, 1918.

NATHAN HATCH.
